UNITED STATES PATENT OFFICE.

CONRAD BAUER, OF PITTSBURG, PENNSYLVANIA.

SCREEN.

1,002,360.

Specification of Letters Patent. Patented Sept. 5, 1911.

Application filed October 12, 1907. Serial No. 397,117.

To all whom it may concern:

Be it known that I, CONRAD BAUER, of Pittsburgh, in the county of Allegheny and State of Pennsylvania, have invented a certain new and useful Improvement in Screens, of which the following is a full, clear, and exact description, reference being had to the accompanying drawings, forming part of this specification, in which—

10 Figure 1 is a perspective view of a window provided with my improved screen; Fig. 2 is a vertical sectional view of the same; Fig. 3 is a front elevation of the screen showing the window-frame in vertical section; Fig. 15 4 is a horizontal sectional view of a portion of the screen and the window-frame showing a portion of the heavy weight or bar in full lines; and Fig. 5 is a detached cross section of the weight or bar showing the manner 20 of attachment to the blind.

My invention relates to improvements in roller fly-screens which may be applied to windows, doors, or other openings.

My invention is especially designed to 25 overcome the difficulties heretofore encountered in the use of wire netting for screens which are not permanently supported in rigid frames; due to the tendency of the stiff material to kink and wrinkle and become misshapen. I have found that spring 30 rollers, such as are used with curtains and cloth fabric, are entirely unsuited to material which has the property of becoming bent and which normally retains a curvature 35 or set as it is unrolled. I have overcome all of the difficulties mentioned by employing a plain roller mounted in suitable bearings upon which the wire netting is wound, and attaching a heavy symmetrical metal bar to 40 the bottom edge of the netting, the bar having sufficient weight to positively stretch all wrinkles and curvature from the netting and to pull it down with a force sufficient to make it hang absolutely taut in any adjust- 45 ed position. Moreover, by using a plain roller instead of a spring roller and weight- 50 ing it in the manner described, the wire netting will be symmetrically balanced and held evenly across the entire width so that there will be no tendency to roll unevenly.

In the drawings, 2 represents the plain roller mounted in suitable bearings, and upon which the wire netting or screen is wound.

To the bottom of the wire netting is secured 55 a heavy metallic bar A, which may be formed of sections 4, 5, secured together by

screws 6, 6^a, and clamping the netting between them. In Fig. 5, the bar-sections 4, 5, are separated by spacing-bars 7, 8, separated vertically from each other to permit the insertion of thin clamping members 9, 10, around which the end of the screen is wrapped in alternate folds and secured. The ends of the spacing-bars 7, 8, project on each side beyond the main bar-sections 4, 5, and slidingly fit into vertical grooves 11 in the window-frame 12. The roller may be provided with any suitable winding and retaining mechanism to coöperate with the weight A. In the mechanism shown, the roller is provided with a gear-wheel 14, adapted to mesh with a gear wheel 15, fixed to a sprocket-wheel 16, which is journaled in a vertically sliding bar 17. The bar 17 is operated by means of the lever-arm 18, which is pivoted to a stationary bracket 19, and is connected with the sliding bar 17 by a slot and pin as indicated at 20. Extending from the outer end of the lever-arm 18, 75 is the rod 21, which is provided with a handle 22, by means of which the rod 21 and lever 18 may be operated to move the bar 17, and to alternately throw the gear-wheel 15 and the locking pin 23 on the bar 17, into engagement with the gear-wheel 15. 80 When the bar 17 is raised, the gear-wheel 15 is placed in mesh with the gear-wheel 14 and the locking pin 23 is simultaneously disengaged. In this position the roller 2 is free to be lowered, or to be rotated in the opposite direction by means of the winding chain 24, to wind the screen upon the roller. When the screen has been lowered into its extended position, the roller 2 is retained and locked by lowering the sliding bar 17 90 until the pin 23 engages the gear-wheel 14. The heavy bar A stretches the wire netting as it is being unwound; removing any kinks and the curvature of the wire so that it will hang perfectly taut and maintains it taut 95 under constant pull when it is in the lowered or extended position.

While I have described in detail the features of construction illustrated in the accompanying drawings, it is to be understood that changes may be made therein without departing from the spirit of my invention or the scope of my claims, which are—

1. In a rolling screen, a wire netting, and a weight secured to the lower end thereof and comprising a plurality of slats arranged to receive in a fold the lower end of the

screen and a plurality of outer slats inclosing and embracing the other slats; substantially as shown and described.

2. In a rolling screen, a wire netting and a weight secured to the lower end thereof and comprising a series of parallel slats arranged to receive in a fold the lower end of the netting and a series of outer slats parallel to and inclosing and embracing the

first named slats and wire fold; substantially as shown and described.

In testimony whereof, I have hereunto set my hand.

CONRAD BAUER.
